UNITED STATES PATENT OFFICE.

FRANK L. VAN DUSEN, OF FORT ERIE, ONTARIO, CANADA.

IGNITING DEVICE.

1,185,027.

Specification of Letters Patent. Patented May 30, 1916.

Application filed August 21, 1913, Serial No. 785,898. Renewed October 20, 1915. Serial No. 57,009.

To all whom it may concern:

Be it known that I, FRANK L. VAN DUSEN, a citizen of the United States of America, and a resident of the village of Fort Erie, Province of Ontario, Dominion of Canada, have invented certain new and useful Improvements in Igniting Devices, of which the following is a full, clear, and exact description.

10 My invention relates generally to igniting devices wherein ignition is produced by the frictional contact of two metals, and has for its principal object to provide a device which may be applied to or made a part of lamp 15 or lantern burners, or the like, for automatically lighting the same.

Another object of my invention has been to provide a device which shall be simple and cheap to manufacture, easy to operate, 20 and one which shall not very readily get out of order.

As is well known, the diameter and pitch of the screw threads on lantern burners are standardized and I have sought to provide 25 an igniting device and lantern burner which is adapted to replace any standard lantern burner without any trouble, inconvenience or fitting on the lantern.

Reference is to be had to the accompanying 30 drawings forming a part of this specification, in which like characters of reference indicate like parts throughout the several views, of which:

Figure 1 is a side elevation of my device 35 with a portion of the wick raiser stem broken away and shown in section. Fig. 2 is a plan view of the same. Fig. 3 is a sectional plan view and is taken on line 3—3 of Fig. 1. Fig. 4 is a sectional elevation of my device and is taken on line 4—4 of Fig. 3. Fig. 5 is a fragmentary sectional view taken on line 5—5 of Fig. 2. Fig. 6 is an enlarged fragmentary view showing the friction wheel and a part of the means 40 for operating the same. Fig. 7 is a sectional view of a portion of my device and is taken on line 7—7 of Fig. 3.

In the drawings, 7 represents the burner of my device and 8 the casing thereof.

50 9 is the wick tube and 10 the wick raiser stem.

11 are the star wheels, which are provided with central square-shaped apertures and 55 slidably mounted upon the square-shaped wick raiser stem 10 and arranged to project inside of the wick tube 9. These star

wheels are arranged in slots provided in a member 12 carried by the casing, whereby movement parallel to the axis of the stem 10 is prevented. Disposed outside of the 60 casing 8 and about the stem 10 is a helical spring 13 which has one end bearing against the casing 8 and the other end against the collar 14, rigidly secured to the stem 10. A tubular casing 15, secured at its inner end 65 to the casing 8, is disposed over the helical spring 13 and collar 14, thus protecting the spring against injury and guiding the outer end of the stem 10 as it is moved in and out. The wick raiser stem is provided at its 70 outer end with a knurled disk 16, by which the same may be rotated and moved axially.

Carried in the lower part of the casing 8 is an inwardly extending square-shaped tube 17. In this tube is slidably arranged 75 a gear rack 18. This rack is provided with a right-angled inwardly extending arm 19, to the inner end of which is pivotally secured the inner end of the wick raiser stem 10, whereby the rack 18 may be moved back 80 and forth by means of the stem. The inner end of the arm 19 is provided on each of its sides with a groove 20, which engages with longitudinal guide-ways 21 carried by the extension 22 of the casing 8, (see Fig. 85 7) whereby the rack is guided throughout its travel. The rack 18 is in mesh with a spur gear 23, which is partially rotated when the rack is operated. This gear is rotatably carried within a casing 24 and is 90 in mesh with a gear pinion 25, which is rotatably mounted at the lower end of the friction wheel shaft 26. A ratchet wheel 27 is also rotatably mounted, upon the shaft 26, above and adjacent to the pinion 25 95 and is secured to the pinion so that it will rotate with the same. The shaft 26 is rotatably carried by the casing parts and has rigidly secured near its lower end a disk 28. This disk is mounted above and adjacent to the ratchet wheel 27, and carried on its under side is a pawl 29, which engages with the teeth on the ratchet wheel 27, and by which engagement the shaft 26 is rotated. At the upper end of the shaft is 100 carried a friction wheel 30, which is provided with a serrated or roughened surface. A piece of pyrophorous metal 31 is provided and is slidably disposed within a holder 32 and has its outer end held in 105 contact with the friction wheel 30 by means of a helical spring 33, also carried by the

110

holder 32. A cap 34 is screw-threaded to the rear end of the holder 32 and bears against the outer end of the helical spring 33, whereby the pyrophorous metal 31 may be conveniently and accurately adjusted.

The casing 8 is provided in its upper surface with an aperture 35 which terminates in a short tube 36. A torch 37 is pivotally carried by the casing and is provided with a cap member 38, which is arranged to enter the opening 35 and to normally close the upper end of the tube 36. A suitable spring 45 is provided for keeping the torch normally in the position shown in the drawings. The torch is preferably formed of a piece of wire bent in the form of a spiral spring and with a tuft of asbestos or non-inflammable material secured thereto, which is held normally in contact with the saturated packing 39 carried in the upper part of the casing 8. The torch 37 is provided with a rearwardly extending arm 40, having its outer end disposed below the pivotal point of the torch. A bell-crank lever 41 is pivotally carried by the casing 8 and has its upper arm in engagement with the arm 40 of the torch. The lower arm of the bell-crank lever 41 extends downwardly and has its extreme lower end in engagement with the upper surface of the gear 23. This gear is provided with a raised cam face 42, which, when the gear is rotated, engages with the lower arm of the lever 41 and causes the same to be slightly rotated, thus raising the torch to its uppermost position. The burner of my device is provided with the usual screw-threaded portion 43, which fits into the oil container 44 of the lamp or lantern, shown in dotted lines in Fig. 1.

When my device is to be operated the wick raiser stem 10 is rotated so as to bring the upper end of the wick in the position shown in the drawing where it can be easily lighted. The wick, having been turned up, the wick raiser stem 10 is now pushed inwardly against the tension of the spring 13, which causes the rack 18 also to be moved inwardly. As the rack 18 is actuated, the gear 23 will be partially rotated, and as it rotates the raised cam-face 42 will contact with the lower end of the bell crank lever 41, which in turn will push the arm 40 of the torch and raise the same into the ignition field, where it will receive the sparks coming from the friction wheel and pyrophorous metal. The friction wheel 30 carried by the shaft 26, is operated through the medium of the gear pinion 25, meshing with the gear 23, and the ratchet wheel 27, pawl 29 and disk 28. It will be clearly seen from the drawings that when the rack 18 is pushed inwardly, the pinion 25 and attached ratchet wheel 27 will be rotated clockwise, and when the ratchet wheel is

will engage with the ratchet pawl carried by the disk 28 rigidly mounted on the shaft 26, and cause the rotation of said shaft and friction wheel in a clockwise direction. When rotated the friction wheel will discharge a series of sparks into the ignition field and against the torch 37.

When the pressure on the wick raiser stem 10 is released, the spring 13 will carry the same back to its normal position as shown in the drawings. As the stem is moved to its normal position, the rack 18 will also be drawn inwardly and cause a reverse rotation of the gear 23. This will move the cam-face 42 out of engagement with the lower end of the bell crank lever 41, and thus allow the spring 45 of the torch to force the cap member 38 down upon the upper end of the tube 36, and thus lower the torch into the receptacle and close the top of the tube 36. When the parts of the device are moving to their normal positions, the gear pinion, together with the ratchet wheel 27, will be rotated in a counter-clockwise direction, and when rotating in this direction the ratchet wheel will be released from its engagement with the pawl 29 and disk 28. Thus, it will be seen, that the shaft 26, friction wheel 30 and disk 28 carried thereby, will be rotated only in one direction and will remain stationary when the parts of the device are moved in the opposite direction, thus throwing the igniting sparks into the ignition field only.

The packing 39 contained in the casing 8 is saturated with a volatile fluid, such as gasolene or the like, and the torch 35 being in contact with the said packing, it also will be saturated with the volatile fluid. Thus, it will be clearly understood, that when the torch 35 is raised in the position shown in dotted lines in Fig. 5, the sparks coming from the pyrophorous metal will cause the volatile fluid in the torch to be quickly ignited. The torch when ignited, being in a position adjacent to the burner, the wick will be lighted therefrom, whereupon the wick raiser stem 10 and the parts connected thereto are permitted to return to their normal positions.

While I have shown and described my invention as applied to a lantern burner, it is obvious that it may be used with equal efficiency, to ignite lamp burners, gas burners, or the like. These and other modifications of the details herein shown and described may be made without departing from the spirit of my invention or the scope of the appended claims, and I do not wish to be limited to the exact embodiment herein shown and described.

Having thus described my invention, what I claim is:

1. An igniting device comprising an oil burner provided with a wick and wick raiser,

- 5 said wick raiser comprising an axially slide-
able and rotatably mounted wick raiser stem
and star wheels slidably and non-rotatably
mounted upon said stem, a torch adjacent to
said wick, said torch being pivotally carried
by a stationary member and movable into
an ignition field, a rotatably mounted fric-
tion wheel arranged to discharge sparks into
the ignition field, a piece of pyrophorous
10 metal held in frictional contact with said
wheel and means operatively connecting said
stem with said torch and friction wheel.
2. An igniting device comprising an oil
burner provided with a wick and wick raiser,
15 said wick raiser comprising an axially slide-
able and rotatably mounted wick raiser stem
and star wheels slidably and non-rotatably
mounted upon said stem, a torch adjacent to
said wick, said torch being pivotally carried
20 by a stationary member and movable into an
ignition field, a rotatably mounted friction
wheel arranged to discharge sparks into the
ignition field, a piece of pyrophorous metal held
in frictional contact with said wheel and gear
25 and ratchet means connecting said stem with said
friction wheel.
3. An igniting device comprising an oil
burner provided with a wick and wick raiser,
30 said wick raiser comprising an axially slide-
able and rotatably mounted wick raiser stem
and star wheels slidably and non-rotatably
mounted upon said stem, said stem retained
in its normal position by spring means, a
35 torch adjacent to said wick, said torch being
pivotally carried by a stationary member and
movable into an ignition field, a rotatably
mounted friction wheel arranged to discharge
sparks into the ignition field and a piece
40 of pyrophorous metal held in frictional
contact with said wheel and means operatively
connecting said stem with said torch and
friction wheel.
4. An igniting device comprising an oil
burner provided with a wick and wick raiser,
45 said wick raiser comprising an axially slide-
able and rotatably mounted wick raiser stem
and star wheels slidably and non-rotatably
mounted upon said stem, a torch adjacent
50 to said wick, said torch being pivotally carried
by a stationary member and movable into an
ignition field, a rotatably mounted friction
wheel arranged to discharge sparks into the
ignition field, a piece of pyrophorous
55 metal held in frictional contact with said
wheel, and means connected with said
stem for imparting motion in one direction
to said friction wheel and in both directions
to said torch.
- 60 5. An igniting device comprising an oil
burner provided with a wick and wick raiser,
said wick raiser comprising an axially slide-
able and rotatably mounted wick raiser stem
and star wheels slidably and non-rotatably
65 mounted upon said stem, a torch adjacent
to said wick, said torch being pivotally carried
by a stationary member and movable into an
ignition field, a rotatably mounted friction
wheel arranged to discharge sparks into the
70 ignition field, a piece of pyrophorous metal held
in frictional contact with said wheel, a spur
gear provided with a cam on its face, means
connecting said gear with said stem and means
connecting said cam with said torch, whereby
75 when said stem is pushed inwardly said
friction wheel will be rotated and said
torch simultaneously raised into the ignition
field.
6. An igniting device comprising an oil
burner provided with a wick and wick raiser,
80 said wick raiser comprising an axially slide-
able and rotatably mounted wick raiser stem
and star wheels slidably and non-rotatably
mounted upon said stem, a pivotally mount-
ed torch adjacent to said wick and movable
85 into an ignition field, a rotatably mounted
shaft disposed adjacent to said torch, a fric-
tion wheel carried at the upper end of said
shaft and arranged to discharge sparks into
the ignition field, a piece of pyrophorous
90 metal held in frictional contact with said
wheel, a gear pinion and a ratchet wheel ro-
tatably mounted upon said shaft, a disk
rigidly secured to said shaft adjacent to
said ratchet wheel, a pawl carried by said
95 disk and engageable with said ratchet wheel
and gear means connecting said stem with
said pinion, whereby said friction wheel is
rotated in one direction only.
7. An igniting device comprising an oil
burner provided with a wick and wick raiser,
100 said wick raiser comprising an axially slide-
able and rotatably mounted wick raiser stem
and star wheels slidably and non-rotatably
mounted upon said stem, a pivotally mount-
ed torch adjacent to said wick and movable
105 into an ignition field, a rotatably mounted
shaft disposed adjacent to said torch, a fric-
tion wheel carried at the upper end of said
shaft and arranged to discharge sparks into
the ignition field, a piece of pyrophorous
110 metal held in frictional contact with said
wheel, a gear pinion and a ratchet wheel ro-
tatably mounted upon said shaft, a disk rigidly
secured to said shaft adjacent to said ratchet
wheel, a pawl carried by said disk and engageable
115 with said ratchet wheel and means connected
with said stem for operating said pinion and
means for simultaneously raising said torch.
8. An igniting device comprising an oil
burner provided with a wick and wick raiser,
120 said wick raiser comprising an axially slide-
able and rotatably mounted wick raiser stem
and star wheels slidably and non-rotatably
mounted upon said stem, a casing for said
burner, a pivotally mounted torch carried
125 by said casing adjacent to said wick and
movable into an ignition field, said torch
having its end normally in contact with the

igniting fluid, a rotatably mounted friction wheel arranged to discharge sparks into the ignition field, a piece of pyrophorous metal held in frictional contact with said wheel and means operatively connecting said stem with said torch and said friction wheel.

9. An igniting device comprising an oil burner provided with a wick and wick raiser, said wick raiser comprising an axially slideable and rotatably mounted wick raiser stem and star wheels slidably and non-rotatably mounted upon said stem, a torch adjacent to said wick, said torch being pivotally carried by a stationary member and movable into an ignition field, means for operating said torch, a rotatably mounted friction wheel arranged to discharge sparks into the ignition field, a piece of pyrophorous metal held in frictional contact with said wheel, a gear rack connected with said stem and slideable therewith and gear means connecting said rack with said friction wheel.

10. An igniting device comprising an oil burner provided with a wick and wick raiser, said wick raiser comprising an axially slideable and rotatably mounted wick

raiser stem and star wheels slidably and non-rotatably mounted upon said stem, a torch adjacent to said wick, said torch being pivotally carried by a stationary member and movable into an ignition field, a rotatably mounted friction wheel arranged to discharge sparks into the ignition field, a piece of pyrophorous metal held in frictional contact with said wheel, a gear rack connected with said stem and slideable therewith, a spur gear meshing with said rack, a cam formed on the face of said spur gear, gear and ratchet means connecting said spur gear with said friction wheel and lever means connecting said cam with said torch, whereby said friction wheel is rotated in one direction and said torch operated in both directions.

In testimony whereof, I have hereunto signed my name in the presence of two subscribing witnesses.

FRANK L. VAN DUSEN.
